UNITED STATES PATENT OFFICE.

JOHN ZILLIOX, OF ORCHARD PARK, NEW YORK.

BOLT KEY.

Application filed June 22, 1923. Serial No. 647,087.

To all whom it may concern:

Be it known that I, JOHN ZILLIOX, a citizen of the United States, residing at Orchard Park, in the county of Erie and State 5 of New York, have invented a new and useful Improvement in Bolt Keys, of which the following is a specification.

This invention relates to a bolt key which is to be used in connection with a key bolt 10 for the purpose of detachably connecting two parts as a substitute for ordinary nuts and bolts.

As is well known the iron work of buildings, ships and similar structures frequently 15 requires a temporary connection before being permanently connected either by means of ordinary bolts, rivets or the like and it is now a common practice to use for this purpose key bolts which can be quickly 20 adapted to the parts for temporarily connecting the same and also quickly detached therefrom after their use is no longer required.

It has been found however that the bolt 25 keys used in connection with such key bolts, as heretofore constructed, had to be made unduly long in order to permit of using the right angle or taper on the same which would avoid slipping back of the bolt key 30 after the same had been tightened, this excessive length being objectionable on account of the amount of material required for their manufacture and also on account 35 of the inability to use this character of bolt in close quarters where the necessary room was not available.

It is therefore the object of this invention to provide a bolt key which is considerably shorter than those now in common 40 use and thus effect a saving in the amount of material which is used and also producing a more compact construction which permits of using this kind of a bolt in cramped quarters, and still permit of readily tightening or driving home with ease and facility 45 and also securely holding the bolt key in place so that the same is not liable to become loose after being tightened.

In the accompanying drawings:

50 Figure 1 is a longitudinal sectional view showing my improved bolt key used in connection with a key bolt for securing together two members. Figure 2 is a cross sectional elevation of the same taken on line 2—2 of Figure 1. Figure 3 is a side elevation of the bolt key showing a slight modification of

its construction as compared with that shown in Figure 1.

Similar characters of reference indicate like parts in the several figures. 60

Although the key bolt in connection with which my invention is to be used may be employed for connecting various members the same is shown in the drawings as applied to the overlapping ends of two metal plates 10, 11, which are detachably connected by the use of a key bolt equipped with one of my improved bolt keys. The key bolt comprises a shank or body 12 passing through corresponding openings in the overlapping plates 10, 11, and provided at the front end with a head 13 which bears against the outer side of the plate 11, while the central part thereof is provided with a longitudinal slot 14, the outer end of which forms 65 a seat, bearing or abutment 15 which is arranged at a distance from the outer side of the plate 10. 70

16 represents the bolt key which is constructed of sheet metal in the form of a 80 plate which is of tapering form and driven with its small end through the outer part of the slot 14 in the bolt shank so that the inner longitudinal edge 17 of this key is arranged at right angles to the axis of the 85 bolt and bears against the outer side of the plate 10, while the outer edge of the key bears against the abutment 15 at the outer end of the slot 14. 90

This outer edge of the bolt key is constructed to form a succession of tightening or wedging inclines or surfaces 18 which are arranged at a comparatively steep angle 95 relatively to the inner or base edge 17 of the key, and a series of holding or retaining surfaces 19 which alternate with the wedging surfaces and are so constructed that they are arranged parallel or nearly parallel with the inner longitudinal edge 17 of the bolt key so that they produce a substantially non-wedging effect. These wedging surfaces and holding surfaces are arranged alternately on the outer longitudinal edge of the bolt key. In the preferred construction the wedging surfaces are inclined at about a 100 seven per cent grade and the holding surfaces at about a two per cent grade. Upon driving such a bolt key through the outer part of the slot in the body of a key bolt the inner longitudinal edge of this key will 105 slide along the adjacent surface of the respective member of those to be coupled, 110

while the inclined outer edge of this bolt key engages its alternate wedging and holding surfaces with the outer abutment of the key bolt until the bolt key has been driven 5 sufficiently tight to reliably hold the parts which are to be coupled securely in place relatively to each other. As each wedging inclined surface engages with the seat or abutment on the key bolt the parts to be 10 coupled are drawn more tightly together, the inclination of these inclines being such as to enable a workman with a hammer, usually employed for this purpose, to drive the bolt key forwardly and obtain the desired 15 tightening effect. The angle for these wedging or tightening surfaces 18, which has been found from past experience to be most satisfactory, is about seven per cent. The retaining or resting surfaces 19 on the 20 inclined edge of the bolt key may either be arranged at a very slight angle relatively to the inner edge 17 of the bolt key, say a grade of about two per cent, as shown in Figure 1, which grade is so slight that when 25 one or the other of these holding or retaining surfaces of the bolt key engages with the seat or abutment of the key bolt the inclination will be so minute that there will be practically no tendency for the bolt key 30 to slip back but instead will form a definite stopping place for the bolt key to engage the key bolt without any tendency of one of these parts slipping with reference to the other and thus insure holding the parts which have been clamped together securely against each other.

If desired however the retaining or holding surfaces of the bolt key can be made perfectly parallel relative to the inner or 40 base edge 17 of the bolt key, as shown at 20 in Figure 3.

By means of this construction of the bolt key the same can be made considerably shorter than bolt keys heretofore in use, thereby effecting a considerable economy on account of the reduced amount of material required and the same also permits of using key bolts in comparatively narrow places where long bolt keys would be prohibited.

The bolt keys heretofore in use in connection with key bolts have had their inclined or outer wedging surface arranged at an angle less than seven per cent grade in order to enable this key to obtain a friction grip on the key bolt and still prevent the key from slipping back or becoming loose in the bolt. This form is particularly objectionable when using a bolt of this character in boiler work, in which case the bolts 55 would become reversed as the boiler was turned and the keys would often drop out

of the bolts when the boiler was vibrated due to the operation of fastening rivets in the same. On the other hand a comparatively steep angle, which would permit of shortening the key, would be objectionable because the same would not give a good hold to the key in the bolt and thus cause the same to loosen. In the present case a comparatively steep angle is employed on the 70 wedging surfaces so as to obtain a quick drawing action of the key in the bolt but after the drawing of each section of the key has been accomplished the bolt is permitted to rest on a comparatively flat, low angle or 75 neutral portion of the key so that the same will stay in the position where it has been driven without any liability of becoming loose. If when driving a key into a bolt the parts are tight when the bolt is in engagement with the higher part of one of the inclined wedging surfaces it is possible by giving the key an extra heavy blow to drive the key sufficiently further to engage the next succeeding holding face with the bolt 80 inasmuch as the metal of the bolt and the key will stretch sufficiently for this purpose and thereby prevent the key from slipping backward and instead holding the bolt under tension.

I claim as my invention:

1. A bolt key comprising a plate adapted to be driven into the slot of a key bolt and provided with forwardly converging inner and outer longitudinal edges, said inner edge being adapted to engage with the adjacent member through which the bolt passes and arranged parallel therewith and the outer edge engaging with the outer end of the slot in the bolt and constructed to form a series of steep wedge surfaces and a series of holding surfaces which alternate with said wedge surfaces and which are arranged to produce a substantially neutral effect.

2. A bolt key comprising a plate adapted to be driven into the slot of a key bolt and provided with forwardly converging inner and outer longitudinal edges, said inner edge being adapted to engage with the adjacent member through which the bolt passes and arranged parallel therewith and the outer edge engaging with the outer end of the slot in the bolt and constructed to form a series of steep wedge surfaces and a series of holding surfaces which alternate with said wedge surfaces and which are arranged at a sufficiently lesser angle relative to said inner edge to produce a non-slipping effect of the key in said key bolt.

In testimony whereof I affix my signature.
JOHN ZILLIOX.
